UNITED STATES PATENT OFFICE

2,521,205

LIFE PRESERVER ATTACHMENT FOR
TWO-PIECE SWIM SUITS

Malham H. David, Chicago, Ill.

Application September 8, 1948, Serial No. 48,258

4 Claims. (Cl. 9—20)

1

My invention relates to inflatable life preserver attachments for swim suits and the like.

An important object of my invention is to provide an inflatable life preserver attachment for swim suits and the like which, when deflated, will fold into a small compact article easily carried in a bag or pocket.

A further object of my invention is to provide an inflatable life preserver attachment which, by means of slide fastener strips attached thereto, is removably attachable to a swim suit or to underwear, having mating slide fastener strips fastened thereon.

A still further object of my invention is to provide an inflatable life preserver attachment which, when attached to a swim suit or underwear, may be used for life preserving purposes, or for swimming instructions, or swimming in deep water.

A further object of my invention is to provide an inflatable life preserver attachment of the above-mentioned character that may be economically produced in large quantities.

Other objects and advantages embraced in my invention will be disclosed in the following description and in the accompanying illustrations, in which like numbers have reference to like parts, and in which:

Fig. 1 is a perspective view of my inflatable life preserver attachment, deflated.

Fig. 2 is an enlarged front view of my invention, inflated.

Fig. 3 is a perspective view of a one piece swim suit or suit of underwear, having mating slide fasteners stitched or attached to the front thereof.

Fig. 4 is a front view showing my inflatable life preserver inflated and attached to a one piece swim suit or suit of underwear.

Fig. 5 is a perspective view showing a two piece suit of underwear or swimming suit, having mating slide fastener strips attached to the upper part and attachable to and detachable from, the lower part thereof.

Fig. 6 is a top view of my inflatable life preserver attachment, taken looking in the direction of lines 6—6 on Fig. 4.

Fig. 7 is a side view of my invention, shown attached to a swimming suit and being worn by a swimmer in the water.

Referring to the illustration, my invention is generally designated 8, and consists of two inflatable tube sections 9, made preferably of rubber, or synthetic rubber, such as used in tire tubes. A tubular collar support and connector

2

10, also preferably made of rubber or synthetic rubber, connects the two upper ends of the said inflatable tube sections 9. An inflating valve 11 is located preferably at the lower end of one of the inflatable tube sections 9, as shown in Fig. 2. Separable slide fastener strips 12 are secured on the inner edges of the two inflatable tube sections, and are provided with slide boxes 13 which are shown on the free ends 14 of the slide fastener strips 12 in Fig. 2. Mating slide fastener strips 14 are stitched, or otherwise attached, preferably along the outside edges of the front of a one piece swim suit or suit of underwear, designated 15, as shown in Fig. 3.

15 Fig. 5 illustrates mating slide fastener strips 24 shown attached to the front of a swim or underwear shirt 16, and having the bottom ends 17 thereof free. On the under sides of the said free ends 17 are secured a number of male snap fas-

20 teners 18, which are attachable to female snap fasteners 20, secured on the forward sides of a pair of swim or underwear trunks, designated 19. When two piece swimming suits or underwear are used in connection with my invention as hereinabove described, the free ends 17 of the mating slide fastener strips 24 on the shirt are secured by the male snap fasteners 18 to the female snap fasteners 20 on the trunks thereof.

25 For use in life preserving purposes my inflatable life preserver attachment 8 may be carried, deflated, in a traveling bag or in the pocket of a coat. A one piece underwear suit, shown in Fig. 3 and designated 15, is worn under the clothes, or a two piece underwear suit, designated 16 and 19 and illustrated in Fig. 5, may be worn.

30 In case of emergency as when a boat is sinking, the outer clothes are removed, the inflatable life preserver attachment 8 is inflated by means of inflating valve 11 and attached to the said underwear by means of the slide fastener strips 12 and mating slide fastener strips 14. The buoyancy of the inflated life preserver attachment 8 will keep a child, or a full grown adult, afloat indefinitely in an upright, or semi-upright, position in the water, as shown in Fig. 7, wherein the swimmer, designated 22, is shown wearing the inflatable life preserver attachment 8 in water, designated 23, with the head maintained above the water. In wearing my inflatable life preserver attachment 8, the collar portion 10 is worn around the neck, as shown in Fig. 7.

35 40 45 50 My inflatable life preserver attachment 8 may also be of considerable value when used in connection with swimming instruction, holding or maintaining the swimmer in the correct position

55

for swimming while learning the various swimming strokes.

A still further important use of my inflatable life preserver attachment would be for children, or untrained swimmers, to wear in swimming pools or beaches where the water is deep. In other words, my inflatable life preserver attachment is of use as a life preserver, as a means of facilitating swimming instructions, and for pleasure in swimming.

A further most important use of my inflatable life preserver attachment would be in connection with trips over water by boat, thereby achieving security against drowning without the necessity of carrying about, or having at hand, the large, heavy and cumbersome life preservers provided for such purposes.

It is to be understood that changes may be made in the construction and in the combination and arrangement of the several parts, provided that such changes fall within the scope of the appended claims.

Having thus disclosed and revealed my invention, what I claim as new and desire to secure by Letters Patent is:

1. Life preserver means comprising a two piece swim suit, separable slide fastener strip means secured longitudinally on each side of the front part of the said swim suit terminating below the waist line, the said slide fastener strip means having a loose terminal portion, snap fastener means on the said loose terminal portion, and mating snap fastener means on the front portion of the lower section of the said two piece swim suit, and inflatable life preserver attachment means comprising, a pair of inflatable tube sections, tubular collar support and connector means securing the said tube sections forming an inverted U shape, valve means provided on one of the said tube sections, and mating separable slide fastener strip means secured to the inner edges of the said tube sections to be detachably assembled to the said first-mentioned slide fastener strip means.

2. Life preserver means comprising a two piece swim suit, separable slide fastener strip means secured longitudinally on each side of the front part of the said swim suit terminating below the waist line, the said slide fastener strip means having a loose terminal portion, snap fastener means on the said loose terminal portion, and mating snap fastener means on the front portion of the lower section of the said two piece swim suit, and inflatable life preserver attachment means comprising, a pair of inflatable tube sections, tubular collar support and connector means securing the said tube sections forming an inverted U shape, valve means provided on one of the said tube sections, and mating separable slide fastener strip means secured to the inner edges of the said tube sections to be detachably assembled to the said first-mentioned slide fastener strip means, the said tube sections being substantially of cylindrical cross-sectional configuration.

3. Life preserver means comprising a two piece swim suit, separable slide fastener strip means

secured longitudinally on each side of the front part of the said swim suit terminating below the waist line, the said slide fastener strip means having a loose terminal portion, snap fastener means on the said loose terminal portion, and mating snap fastener means on the front portion of the lower section of the said two piece swim suit, and inflatable life preserver attachment means comprising, a pair of inflatable tube sections, tubular collar support and connector means securing the said tube sections forming an inverted U shape, valve means provided on one of the said tube sections, and mating separable slide fastener strip means secured to the inner edge of the said tube sections to be detachably assembled to the said first-mentioned slide fastener strip means, the said collar support and connector means being substantially of cylindrical cross-sectional configuration and/or relatively smaller diametral magnitude than that of the said tube sections.

4. Life preserver means comprising a two piece swim suit, separable slide fastener strip means secured longitudinally on each side of the front part of the said swim suit terminating below the waist line, the said slide fastener strip means having a loose terminal portion, snap fastener means on the said loose terminal portion, and mating snap fastener means on the front portion of the lower section of the said two piece swim suit, and inflatable life preserver attachment means comprising, a pair of inflatable tube sections, tubular collar support and connector means securing the said tube sections forming an inverted U shape, valve means provided on one of the said tube sections, and mating separable slide fastener strip means secured to the inner edges of the said tube sections to be detachably assembled to the said first-mentioned slide fastener strip means, the said tube sections being substantially of cylindrical cross-sectional configuration, the said collar support and connector means being substantially of cylindrical cross-sectional configuration and of relatively smaller diametral magnitude than that of the said tube sections.
